STOP MOTION FOR WINDERS

Filed Oct. 18, 1922

2 Sheets-Sheet 2

UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

STOP MOTION FOR WINDERS.

Application filed October 18, 1922. Serial No. 595,417.

This invention relates to a machine particularly designed for winding yarn on the spools used in weaving moquette carpet. It is desirable that a substantially uniform length of yarn should be placed on each spool, so that a minimum amount of yarn may remain on the spools after the desired number of patterns have been woven.

It is the object of my invention to provide a simple and effective device by which the winder may be stopped at the end of a predetermined period of operation.

A further object is to so arrange and apply the stop motion that the winder remains at all times under the control of the operator and may be started and stopped as desired during the winding of a spool without interfering with the accurate operation of the stop motion at the determined point. To this end, my invention contemplates such a relation between the stop motion and the manual control mechanism that the operation of the stop motion is effective to disable the control mechanism in all positions thereof.

My invention further relates to arrangements and combinations of parts which will be hereinafter described and more particularly pointed out in the appended claims.

30 A preferred form of my invention is shown in the drawings in which

Fig. 1 is a side elevation of parts of a winder embodying my invention;

Fig. 2 is an enlarged side elevation of certain parts shown in Fig. 1;

Fig. 3 is a detail plan view, looking in the direction of the arrow 3 in Fig. 1;

Fig. 4 is a detail sectional elevation, taken along the line 4—4 in Fig. 3;

40 Fig. 5 is a front elevation of the mechanism shown in Fig. 1, and

Fig. 6 is an enlarged front elevation of certain parts shown in Fig. 5.

Referring to the drawings, I have shown 45 a winder of the general type disclosed in my prior Patent No. 1,337,727, issued April 20, 1920 and comprising a frame 10 supporting a measuring roll 11 having connections (not shown) to a driving shaft 12 rotatable in

50 bearings in the lower part of the frame 10. A driving pulley 13 is loosely rotatable on the shaft 12 and may be forced outward against a friction disc 14 to rotate the shaft 12.

55 The pulley 13 is provided with a hub

having a groove 15 which receives blocks 16 mounted on the forked arms of a lever 17 secured to a clutch shaft 18. A bell crank 19 is fixed to the end of the shaft 18 and the upwardly extending arm of the bell crank 60 pivotally supports a control lever 20.

An arm 21 of the lever 20 is connected by toggle members 22 to the horizontally extending arm 23 of the bell crank 19. A spring 24 normally maintains the toggle 65 members 22 in the operative relation shown in Fig. 5, determined by a stop 25.

An arm 26 is associated with the lower toggle member 22 and is connected by a link 70 or chain 27 to an arm 28 on a rock shaft 29. The shaft 29 is mounted in bearings on the frame 10 and supports a second arm 30 having a pin and slot connection with the lower end of a stop lever 31. The upper end of the lever 31 engages the face of a disc 32 75 having a positive worm and gear driving connection from the measuring roll 11. The pitch of the worm and the size of the gears may be selected to cause the disc 32 to rotate once for any desired number of revolutions of the measuring roll 11.

The disc 32 is provided with a notch or recess 33 at one point in its circumference and a spring 34 causes the upper end of the lever 31 to enter the notch whenever the end of the lever is in alignment therewith. A hand lever 35 is provided on the shaft 29 for resetting the device as will be hereinafter described.

The control lever 20 is commonly provided 80 with a knee pad 36 at its upper end by which it may be moved to the left to cause the pulley 13 to engage the disc 14 and start the winder. A heavy coil spring 37 (Fig. 1) acts to immediately disengage the driving 85 connections as soon as pressure on the pad 36 is released. A link 38 connects the lever 20 to a similar lever at the opposite side of the machine, as fully disclosed in my prior patent, thus permitting the machine to be 90 controlled from either side.

Having thus described the construction of my improved winder, the operation thereof is as follows:

The gearing between the measuring roll 11 105 and the disc 32 is first selected so that the measuring roll will pass the desired length of yarn while the disc 32 is completing a single revolution. Assuming that the machine has been stopped with the end of the 110

lever 31 disposed in the notch 33, a new spool is placed in the machine and the winder is started by pressure upon the pad 36 of the control lever 20. The machine continues in operation until the disc 32 completes its single revolution, during which time, however, it may be started and stopped by the operator as desired by applying and releasing pressure on the pad 36.

When the revolution of the disc 32 is completed, the end of the lever 31 enters the notch 33, the chain or link 27 is pulled upward, and the lower toggle member 22 is rocked to break the toggle, as indicated by the arrow *a* in Fig. 6. The bell crank 19 is thus released, regardless of the position of the control lever 20, and the spring 37 promptly disconnects the driving pulley 13. In order to start the machine, it is necessary to first use the handle 35 to withdraw the lever 31 from the notch 33 and to relieve the tension on the chain 27, permitting the spring 24 to restore the toggle members 22 to their original position. While the lever 31 is thus held out of the notch 33, the machine may be started by the usual pressure upon the pad 36 of the lever 20.

It is thus evident that I have so arranged my stopping mechanism that the machine remains at all times under the direct control of the operator, except at the point when the disc 32 completes its revolution, at which point the manual control mechanism is disabled and the machine is stopped regardless of the application of pressure on the lever 20.

Having thus described my invention, I do not wish to be limited to the details herein disclosed otherwise than as set forth in the claims but what I claim is:—

1. A winder having, in combination, a measuring roll, driving mechanism therefor, means to make and manually maintain a driving connection to said driving mechanism, and a stopping device effective to disable said manual means and stop said measuring roll while said manual means remains in its normally operative position.

2. A winder having, in combination, a measuring roll, driving mechanism therefor, a manual shifting lever for said driving mechanism, a connection through which said lever is effective to render said driving mechanism operative to drive said measuring roll, and automatic means effective to disable said connection and stop said roll after a predetermined actuation thereof and while said shifting lever remains in its normally operative position.

3. A winder having, in combination, a measuring roll, driving mechanism therefor, including a clutch operating shaft, a manually operated controlling lever for said shaft, means to connect said lever rigidly with said shaft, and automatic devices effective to disable said connecting means and release said shaft from said manually operated controlling lever.

4. A winder having, in combination, a measuring roll, driving mechanism therefor, a manually operated controlling device for said mechanism freely movable to operative position, and additional and automatic means effective to disable said manually operated controlling device and thereby cause disengagement of said driving mechanism while said controlling device remains freely movable and in its normally operative position.

5. In a winder, a measuring device, driving mechanism, and control means for said driving mechanism, said control means including a clutch, a clutch operating shaft, a bell crank fixed thereon, a control lever pivoted to one arm of said bell crank, a toggle connection between said lever and the other arm of said bell crank, and means to break said toggle connection, said latter means being normally held out of operation by said measuring device during a predetermined operation of said measuring device.

In testimony whereof I have hereunto affixed my signature.

EPPA H. RYON.
